CLAIM

The ornamental design for a protective case for a calculator or the like, as shown and described.

DESCRIPTION

FIG. 1 is a top perspective view of a protective case for a calculator or the like showing my new design;
FIG. 2 is an inverted bottom perspective view thereof with the latch partly open;

FIG. 3 is an inverted bottom rear perspective view of FIG. 1;

FIG. 4 is a top rear perspective view of FIG. 1; and

FIG. 5 is a top perspective view thereof in the open position showing both top and bottom surfaces.

FIG. 1.

FIG. 2.

FIG. 3.

FIG. 4.
